UNITED STATES PATENT OFFICE.

ADAM K. ORZUCHOWSKI, OF ELLIS ISLAND, NEW YORK.

RAILWAY CONSTRUCTION.

1,406,887.

Specification of Letters Patent. Patented Feb. 14, 1922.

Application filed December 7, 1921. Serial No. 520,567.

To all whom it may concern:

Be it known that I, ADAM K. ORZUCHOWSKI, a citizen of Poland, residing at Ellis Island, in the county of New York and State 5 of New York, have invented certain new and useful Improvements in Railway Constructions, of which the following is a specification.

This invention relates to certain new and 10 useful improvements in railway constructions and has particular reference to the improved cooperative construction of railway rail sections and cross ties therefor whereby a railway may be constructed of durable and 15 simple form without the employment of bolts and nuts for retaining the parts in operative relation.

With the above general object in view and others that will appear as the nature 20 of the invention is better understood, the invention consists in the novel form, combination and arrangement of parts herein-after more fully described in connection with the accompanying drawings and in 25 which like characters of reference indicate similar parts throughout the views.

In the drawings,

Figure 1 is a fragmentary view partly in 30 top plan and section and partly broken away of a railway constructed in accordance with the present invention,

Figure 2 is a transverse sectional view taken substantially upon line II—II of Figure 1,

Figure 3 is a fragmentary side elevational 35 view of a portion of the device shown in Figure 1 with an additional tie at one side of the joint shown in Figure 1,

Figure 4 is a fragmentary perspective 40 view of one of the rail sections employed in railway construction according to the present invention, and

Figure 5 is a perspective view of one of the ties employed in Figure 1.

Referring more in detail to the several 45 views, the present invention, in its preferred embodiment consists in placing a plurality of rail sections 5 in end to end relation and forming each of said rail sections with intermediate base flanges 6 having the ends of the same oppositely tapered as clearly shown in Figures 1 and 4, the flanges 6 being spaced from end base flanges 7 of the rail section as at 8 and the flanges 7 being tapered at 55 their inner portions in a direction opposite to the taper of the adjacent ends of the

flanges 6 and the spaces as at 8 between the flanges 6 and 7 being greater in size than the widths of the cross ties 9 which are employed in the construction.

One base flange 7 of each rail section at each end of the latter is laterally enlarged as at 10 and this enlargement at one end of the rail section is provided with a dove-tail tongue or projection 11 while the lateral 60 enlargement 10 at the other end of the rail is provided with a complementary dove-tail recess 12 (see Figure 1) so that when the rail sections are disposed in proper end to end relation, the tongue 11 of each rail section will interlockingly engage in the recess 65 12 of the adjacent rail section for effectively holding said rail sections in abutting relation as well as in proper alinement.

The ties 9 may be of either metallic or 70 wooden construction and each of said ties is provided with transverse undercut recesses at the ends of the same as at 13, which recesses are of corresponding tapered form to the tapering ends of the flanges 6 75 and 7 while the entrance slots of said undercut recesses or grooves 13 are of such size as to snugly receive the web portion of the rail section so that when the ties are positioned as indicated by dotted lines in Figure 1 coincident with the spaces 8, said ties may be slid in either direction as indicated by the arrow —a— for engaging the flanges 6 or 80 7 and until the ties are wedged in tight engagement with said flanges for securely 85 holding the rail sections to the ties. In order to additionally guard against accidental movement of the ties in a direction to disengage from the flanges 6 or 7, the portions of the walls of the grooves or undercut recesses 13 which engage the edges of the flanges 6 and 7 may be roughened or transversely corrugated as at 14 and the ties 9 may be provided with longitudinal substantially 90 V-shaped ribs 15 centrally of their bottom faces for engagement with the roadbed so as to effectively prevent such shifting of the ties as would cause disengagement of the same from the flanges 95 6 and 7.

In order to prevent accidental disengagement of the dove-tail tongues 11 from the recesses 12 by relative vertical displacement of the connected rail ends, a further tie of special form as indicated by the numeral 16 100 is employed at each rail joint. These ties 105 each are of substantially the same construc-

- tion as the ties 9 except that the undercut recesses of the same are formed larger in order to accommodate the enlargements 10 so as to provide a portion of the tie overlying each tongue and groove 11 and 12 for holding the connected portions 10 in the same horizontal plane. The undercut recesses of the ties 16 may have their walls roughened similar to the ties 9.
- 10 The ties 16 are also illustrated with bottom V-shaped ribs 16' adapted to engage the roadbed for preventing shifting of these ties.
- In operation, the required number of ties 15 are slid onto the flanges 6 and 7 of each pair of rail sections by initially positioning the same as indicated by dotted lines in Figure 1 and with one tie 16 located thereon for the joint with the next succeeding pair of rails.
- 20 Said next succeeding pair of rails are then interlocked with the first by means of the dove-tail tongues and grooves 11 and 12 and the tie 16 is then slid to cover this dove-tail joint as shown in Figure 1 so that the rails 25 are effectively connected.
- It will thus be seen that the invention is extremely simple and embodies construction whereby a railway may be cheaply and quickly constructed without requiring the use of bolts and nuts which have heretofore been found objectionable for various reasons.
- It is believed that the construction and operation of the present invention will be readily understood and appreciated by those 35 skilled in the art from the foregoing description. Minor changes may be made without departing from the spirit and scope of the invention.
- What is claimed as new is:
- 40 1. Railway construction including rail sections each formed with opposite central base flanges having the ends of the same oppositely tapered, end base flanges spaced from the central flanges and having their 45 inner portions oppositely tapered, an end flange at one end of said rail section being laterally enlarged and provided with a dove-tail tongue and the corresponding end flange at the opposite end of the rail section being provided with a complemental lateral enlargement formed with a dove-tail 50 recess of a form and size to receive said dove-tail tongue.
2. Railway construction including rail sections each formed with opposite central base flanges having the ends of the same oppositely tapered, end base flanges spaced from the central flanges and having their 55 inner portions oppositely tapered, an end flange at one end of said rail section being laterally enlarged and provided with a dove-tail tongue and the corresponding end flange at the opposite end of the rail section being provided with a complemental lateral enlargement formed with a dove-tail 60 recess of a form and size to receive said dove-tail tongue.
3. Railway construction including rail sections each formed with opposite central base flanges having the ends of the same oppositely tapered, end base flanges spaced from the central flanges and having their 65 inner portions oppositely tapered, an end flange at one end of said rail section being laterally enlarged and provided with a dove-tail tongue and the corresponding end flange at the opposite end of the rail section being provided with a complemental lateral enlargement formed with a dove- 70 tail recess of a form and size to receive said dove-tail tongue, and a rail joint tie having transverse undercut recesses in the ends of the same providing lips adapted to overhang the interlocked tongues and recesses of adjacent pairs of rail sections whereby disengagement of said tongues from said recesses is prevented.
3. Railway construction including rail sections each formed with opposite central 75 base flanges having the ends of the same oppositely tapered, end base flanges spaced from the central flanges and having their inner portions oppositely tapered, an end flange at one end of said rail section being 80 laterally enlarged and provided with a dove-tail tongue and the corresponding end flange at the opposite end of the rail section being provided with a complemental lateral enlargement formed with a dove-tail 85 recess of a form and size to receive said dove-tail tongue, a rail joint tie having transverse undercut recesses in the ends of the same providing lips adapted to overhang the interlocked tongues and recesses of 90 adjacent pairs of rail sections whereby disengagement of said tongues from said recesses is prevented, and further intermediate cross ties having undercut recesses of tapering form at their ends adapted to be 95 disposed between the adjacent ends of the base flanges of the rail section and slidably wedged onto the tapering portions of said flanges.
4. Railway construction including rail 100 sections each formed with opposite central base flanges having the ends of the same oppositely tapered, end base flanges spaced from the central flanges and having their inner portions oppositely tapered, an end 105 flange at one end of said rail section being laterally enlarged and provided with a dove-tail tongue and the corresponding end flange at the opposite end of the rail section being provided with a complemental lateral enlargement formed with a dove-tail 110 recess of a form and size to receive said dove-tail tongue, a rail joint tie having transverse undercut recesses in the ends of the same providing lips adapted to overhang the interlocked tongues and recesses of adjacent pairs of rail sections whereby disengagement of said tongues from said recesses is prevented, and further intermediate cross ties having undercut recesses of 115 tapering form at their ends adapted to be disposed between the adjacent ends of the base flanges of the rail section and slidably wedged onto the tapering portions of said flanges.
4. Railway construction including rail 120 sections each formed with opposite central base flanges having the ends of the same oppositely tapered, end base flanges spaced from the central flanges and having their inner 125 portions oppositely tapered, an end flange at one end of said rail section being laterally enlarged and provided with a dove-tail tongue and the corresponding end flange at the opposite end of the rail section being provided with a complemental lateral enlargement formed with a dove- 130 tail recess of a form and size to receive said dove-tail tongue, and a rail joint tie having transverse undercut recesses in the ends of the same providing lips adapted to overhang the interlocked tongues and recesses of adjacent pairs of rail sections whereby disengagement of said tongues from said recesses is prevented.
5. Railway construction including rail sections each formed with opposite central base flanges having the ends of the same oppositely tapered, end base flanges spaced from the central flanges and having their inner 135

- portions oppositely tapered, an end flange at one end of said rail section being laterally enlarged and provided with a dove-tail tongue and the corresponding end flange at 5 the opposite end of the rail section being provided with a complementary lateral enlargement formed with a dove-tail recess of a form and size to receive said dove-tail tongue, a rail joint tie having transverse 10 undercut recesses in the ends of the same providing lips adapted to overhang the interlocked tongues and recesses of adjacent pairs of rail sections whereby disengagement of said tongues from said recesses is 15 prevented, and further intermediate cross ties having undercut recesses of tapering form at their ends adapted to be disposed between the adjacent ends of the base flanges of the rail section and slidably wedged onto the tapering portions of said 20 flanges, portions of the walls of the undercut recesses of the ties being adapted to engage the longitudinal edges of said base flanges and being roughened to have anti-slipping engagement with said flanges when 25 wedged onto the latter, and central longitudinal substantially V-shaped ribs on the under surfaces of said ties arranged to wedge into the roadbed for preventing lateral shifting of said ties. 30

In testimony whereof I affix my signature.
ADAM K. ORZUCHOWSKI.
